UNITED STATES PATENT OFFICE.

LOUIS P. DISS, OF ILLION, NEW YORK, ASSIGNOR TO E. REMINGTON & SONS,
OF SAME PLACE.

MAGAZINE FIRE-ARM.

SPECIFICATION forming part of Letters Patent No. 356,275, dated January 18, 1887.

Application filed July 22, 1886. Serial No. 202,818. (No model.)

To all whom it may concern:

Be it known that I, LOUIS P. DISS, of Ilion, in the county of Herkimer and State of New York, have invented certain new and useful 5 Improvements in Fire-Arms, of which the following is a specification.

My invention relates to that class of firearms known as "bolt-guns," and more especially to those which have a magazine arranged to feed the cartridges sidewise up through an opening in the bottom of the receiver, from whence they are shoved forward by the bolt into the chamber of the barrel; and the invention consists in a number of improvements, 15 hereinafter specified.

Figure 1 is a perspective view of a portion of a gun, showing the breech mechanism with the bolt partially retracted. Fig. 2 is a similar view with the breech closed. Fig. 3 is a transverse vertical section of the receiver on the line xx of Fig. 2. Fig. 4 is a longitudinal vertical central section; and Figs. 5 to 18, inclusive, represent the parts in detail.

The first part of my invention relates to the 25 construction of the bolt and its attachments, the object being to so construct and arrange these parts as to facilitate the mounting and dismounting of the same. For this purpose I construct the bolt in two parts, the main 30 portion C (shown detached in Fig. 7) being provided with the usual top rib, C', and preferably, though not necessarily, with a lug, g, on the opposite side, to engage in a recess in the receiver to assist in locking the bolt securely in place when the breech is closed. The other portion of the bolt consists of a 35 nose-piece, G, (shown detached in Fig. 11,) this nose-piece, at its front end, being made of a diameter corresponding with that of the bolt 40 C, but having its body reduced in diameter, so as to fit within the front end of the bolt, which is made tubular to receive it, as shown in section in Fig. 4. On the upper side of this 45 nose-piece G, I make a laterally-projecting flange, G', as shown in Figs. 6, 10, and 11, which, when the bolt is in position in the gun, will project upward in rear of the chamber in the barrel, as shown in Figs. 1, 2, and 4, to serve as a gas check or deflector, and thus prevent 50 the gas from a defective cartridge from

being forced back into the face of the soldier or person using the gun. I connect the nose-piece to the bolt in such a manner that it is caused to move to and fro with the bolt, but does not turn with the bolt. This I accomplish by forming an annular groove, h, in the exterior surface of the nose-piece, as shown in Fig. 11, with a longitudinal groove extending from the groove h backward to the rear end, this groove being shown in Fig. 9, and indicated by the dotted line in Figs. 10 and 11. A pin, i, (shown in section in Fig. 4 and in dotted line in Fig. 6,) is inserted through the wall of the bolt C in such a position that when the nose-piece has its stem inserted into the bolt the end of the pin will enter the longitudinal part of the groove and pass into the annular portion h as the nose-piece is shoved back, and then turned partly over, thus forming what may be termed a "bayonet-joint," 70 by which the nose is secured to the bolt in such a manner as to be moved with it as the bolt is shoved forward or drawn back, but is free to remain stationary when the bolt is turned to lock or unlock it.

I also provide a rigid extractor, which is shown detached in Figs. 8 and 12. The body H of this extractor consists of a solid piece of metal hollowed out longitudinally, so as to fit upon the exterior of the bolt C, like a sleeve, 80 as shown in Fig. 1, for about one-fourth of the circumference of the bolt. On its under side it has a transverse groove, a', to engage with a corresponding lug or projection, h, on the top of the bolt, as shown in Fig. 4, the lug h being 85 shown also in Fig. 7, by which it is secured to the bolt in such a manner as to cause it to move to and fro with the bolt, but permit the bolt to be turned independently of the extractor, the same as in the case of the nose-piece, as already explained. At its front the body H has an offset or shoulder, m, from which a rigid hook, H', projects forward, as represented in Figs. 1, 6, 8, and 12, the inner face of this hook, at its forward end, being beveled, as shown, 95 to cause it to ride up over the flange of the cartridge when thrust forward by the closing of the breech, there being a recess formed in the rear end of the barrel for this hook to enter, as shown in Figs. 1 and 2.

On the under side of the arm or hook H' , near the body, I make a projection, e' , (shown in Fig. 8, and by dotted lines in Fig. 12,) which, when the parts are put together, rests in a recess, e'' , Fig. 11, on the side of the nose-piece G , thus serving to lock the extractor and nose-piece together, so that they cannot rotate independently of each other. The prime object of this projection e' , however, is to form a gas-check to prevent the passage of any gas backward at that point, this projection e' occupying a position transversely in line with the gas-deflector G' . The rib C' on the top of bolt C is undercut, as shown in Fig. 4, and the rear end, l' , of the body H of the extractor is extended back a corresponding distance, as shown in Figs. 8 and 12, this extended portion being of a width equal to that of the rib C' of the bolt, and of such a thickness as to fit in the under-cut, so that when the bolt is turned to the right, or into the locked position, the end of the rib will rest over or upon this rearwardly-extended portion of the extractor H , thus holding it down upon the bolt. The top of the rib C' is recessed or cut out, as shown in Figs. 4 and 6, and has a pin, f , passed through it transversely, as shown. Upon the top of the rib C' , I place a very stiff spring, d , as shown in Fig. 4, there being formed on the under face of this spring a hook-shaped lug, e , which, when the spring is forced back, engages under said pin f , thereby locking the spring securely in place.

The front end of the spring d is provided on its under side with a projection, e' , which bears upon the extractor H and rests in front of the projection e'' on the extractor, as shown in Figs. 1, 2, and 4, when the bolt is turned to the unlocked position, the projection e'' being simply to add strength at that point.

It will be observed that the extractor hook H' always rests upon the upper edge of the right-hand wall of the receiver A and slides back and forth thereon, while the spring d , at the time the bolt is thrust forward to close the breech, rests against the left-hand side or portion of the body H , and is in line with the hook H' only when the bolt is turned to the locked position, it being shown in the former position in Fig. 1 and in the latter position in Fig. 2.

It will also be observed that the width of the deflector G' and the hook H' combined is just sufficient to fill transversely the opening in the top of the receiver, and hence the nose-piece G , with its gas-deflector, and the extractor H are prevented from partaking of the rotary motion of the bolt C , but are free to move with the bolt to and fro in a right line. The shoulder m of the extractor also serves as a stop to limit the backward movement of the bolt by striking against the rear shoulder on the right-hand wall of the receiver. At the rear end of the extractor-spring d a portion is cut away for about one-half the width of the spring, thus leaving a small notch or space, r , as shown clearly in Figs. 1 and 2, for the purpose of permitting the insertion of the point

of the screw-driver, (which accompanies each gun,) and by which the spring d can be pried or forced forward until the hook or lug e is disengaged from the pin f , when the spring can be removed. When this spring is removed and the bolt slightly retracted, the extractor H can be lifted out, and when that is done the deflector G' can be turned to the right until its edge rests on the wall of the receiver, when the nose-piece G can be drawn forward and disengaged from the bolt C , when the latter is free to be drawn backward out of the receiver.

The firing-pin a consists of a rod extending through the center of the bolt its entire length, and projecting slightly at the rear end, where it is secured to the cocking-piece D by a flanged nut, b , as shown in Fig. 4, the firing-pin a being provided with a screw-thread at its rear end, so that by turning the nut b the point of the firing-pin can also be adjusted as may be desired. In order to lock this nut b in position after the firing-pin has been adjusted and prevent it from being accidentally turned by the jar or concussion, it has a hole bored through its flange in line with a pin, c , which projects from the rear end of the cocking-piece D , so that when the firing-pin is pressed back the nut b can be turned until the firing-pin is adjusted, after which it is only necessary to bring the hole in the nut in line with the pin c , when the pressure of the spring n will draw the nut b firmly against the rear end of the cocking-piece D , causing the pin c to enter the hole in the flange of nut b , as shown in Fig. 4.

The mainspring n rests at its rear end against an annular shoulder formed within the bolt C by counterboring the same from the front back to that point, and at the front the spring bears against a collar, v , on the firing-pin, as shown clearly in Fig. 4. Another shoulder, v' , is formed within the bolt, at the point to which the collar v is drawn back when the gun is at full-cock, by boring the bolt out from the front back to that point, as shown in Fig. 4, the collar v being of such a diameter as to permit it to slide freely within this enlarged bore. In order to prevent the possibility of an accidental explosion by the protrusion of the point of the firing-pin when the bolt is shoved forward, I insert a pin, i' , Figs. 4 and 6, through the wall of the bolt C at a point in line with the front edge of collar v when the point of the firing-pin is drawn back even with the front end of the nose-piece G , or a little more, this pin i' thus forming a stop against which the collar v may rest, thus holding the firing-pin back, so that its point cannot protrude beyond the face of the bolt at any time except when the bolt is in the locked position ready for firing.

To enable the collar v to pass the pin or stop i' , as is necessary when the gun is to be fired, I cut a slot or opening, v' , through the collar on one side, as shown clearly in Fig. 14, so that when the bolt is turned to the locked

position the pin or stud i' will be brought into line with this slot v' , when of course the firing-pin will be free to move forward as far as may be necessary to ignite the charge.

5 In order to hold the firing-pin from turning, and thus be sure that this slot v' shall always be in its proper position in line with the pin i' at the time of firing, I form a longitudinal groove, o , in one side of the firing-pin a , at 10 its rear end, as shown in Figs. 4 and 13, and insert a guide-pin, p , through the wall of the cocking-piece D , so its inner end will rest in the groove o , as shown in Fig. 4, thus preventing the firing-pin from turning, but leaving it 15 free to slide forward and back. It is obvious that the relative position of this slot o and its guide-pin, the slot v' in the collar v , and the pin or stud i' in the bolt must be such that when the bolt is in the locked position, ready 20 for firing, the slot v' must be in line with the pin or stud i' , but at all other times they will be out of line, and hence the firing-pin will be held back with certainty until the bolt is shoved forward to close the breech, and it is 25 locked fast by turning its handle so as to cause the rear end of rib C' of bolt C to engage with the shoulder on the receiver.

The cocking-piece D (shown detached in Fig. 5) is a short tubular piece fitted against 30 the rear end of bolt C , and is provided with an enlargement or flange at its rear end, by which it can be drawn back to cock the arm, or can be let down from the cocked position when desired. At its lower side it has an 35 arm, D' , arranged to project forward along the under side of the bolt C , as shown in Fig. 4, this arm being provided with a half-cock notch, n' , in which the sear E engages, said sear engaging with the front end of said arm D' 40 when at full-cock.

The bolt C is provided at its rear end with two longitudinal grooves, s , connected by a transverse groove, s' , as shown in Fig. 7, in which a stud, u , on the upper face of arm D' , 45 Figs. 4 and 5, moves. When the gun is at half-cock, the lug u rests in one of the grooves s , midway between the end of the bolt and the transverse groove s' , and thereby prevents the bolt from being turned or unlocked while the 50 gun is at half-cock.

In order to retract the firing-pin in the act of unlocking the breech-bolt, I make an incline, t , on the arm D' of the cocking-piece, near its front end, as shown in Fig. 5, and on 55 the under side of the bolt C , at a corresponding point, I locate a lug or pin, j , as shown in Fig. 7, so that when the bolt is turned to unlock it this pin j will operate on the incline t , and thus force back the cocking-piece D and 60 the firing-pin connected thereto.

At the end of the incline I form a recess or notch, y , in which the pin j engages and rests when the bolt is unlocked, as indicated by the dotted lines in Fig. 6, the recess being clearly 65 shown in Fig. 5, the object of this recess being to hold the parts in position and counteract the tendency there otherwise would be for the

incline, which is forced against the pin j by the pressure of the mainspring, to throw or turn the bolt back to the locked position. 70 The retraction of the firing-pin depends on the relative position of the nut b on the firing-pin, the incline t on the cocking piece or arm D' , and the stud j on the bolt C , and by means of the nut b these can be adjusted to their 75 proper positions.

In order to remove the firing-pin and the cocking-piece from the bolt, it is only necessary, after the bolt has been removed from the gun, to press against the front end of the firing-pin and force it back far enough to disengage the flange of nut b from the pin c of the cocking-piece, when the nut can be unscrewed from the firing-pin, and all are then free to be taken apart, and that without the aid of any tools 85 whatever. Thus it will be seen that the entire breech mechanism, consisting of the bolt, its nose-piece, the extractor, firing-pin, mainspring, and cocking-piece, can be dismounted or assembled without the use of any tool, except a screw-driver, jackknife, or any similar implement to loosen the spring d , as previously explained.

Another important feature of my invention 90 consists in certain improvements by which the magazine can be loaded through the receiver, and without detaching the magazine.

The magazine M , as is usual in this style of gun, is located directly under the receiver, in such a manner as to force the cartridge sidewise up through an opening in the bottom of the receiver until the upper side of its head is in line with the bolt, when the forward movement of the bolt shoves it forward into the chamber of the gun. As heretofore constructed 100 these magazines have been held in position by a spring-catch, m' , as shown in Fig. 4; but with my present improvements this spring-catch may be dispensed with, and the magazine may be permanently secured to the arm by a 105 pin, o' , as shown in Fig. 16, though either plan may be used, as preferred.

The magazine M is made without any spring-detent, and without any lips along its rear upper edge, thus leaving its mouth open the full 110 width of the cartridge; and the hole through the bottom of the receiver is in like manner made the full width of a cartridge, so that the cartridges can be shoved sidewise down through the receiver into the magazine, as 115 illustrated in Fig. 16.

To hold the cartridges in the magazine and prevent them from being all forced upward in a body by the spring of the magazine, I provide two spring-lips, P , (shown detached in Fig. 125 18,) and apply them to the receiver, as shown in Fig. 17, their spring-arms being secured to the outer walls of the receiver by a screw at their front ends, as shown in dotted lines, Fig. 17, while the rigid lips protrude through 130 slots cut obliquely in a horizontal line through the side walls of the receiver, as shown clearly in Figs. 15 and 17. These lips P are of such a width that their inner edges, when in their

normal position, project a short distance into the space or opening within the receiver, just over the rear part of the mouth of the magazine, as shown in Figs. 15 and 17, they being shown pressed outward by the cartridges as they pass from case O in the former figure. These lips P, being thus located, serve not only to hold the cartridges in the magazine M, but they also serve as a floor to prevent the cartridge, which is laid in the receiver when the gun is to be used or charged as a single-loader, from falling through the opening below. Their distance apart and their inclination are such as to permit the head of the cartridge in the magazine below to protrude high enough to be struck by the face or nose of the bolt when the latter is shoved forward, the same as with the magazines formerly used, the only difference being that in the former the lips on the sides of the magazine held the cartridges from rising above a certain point, whereas in this these spring lips do that.

It will readily be seen that the magazine can be loaded or filled by inserting the cartridges one at a time into it, the inclination of the lips P causing their inner edges to present an inclined surface to the cartridge laid upon them, so that by pressing on the cartridge the lips are pressed outward far enough to let the cartridges through, when they immediately spring inward over the cartridge, and thus hold it in the magazine.

In order to facilitate the filling of the magazine, I provide a packing-case, O, of the proper size to contain sufficient cartridges to fill the magazine, (which will form the subject of a separate application, and therefore is not fully described herein, except so far as is necessary to show its application in connection with my improved gun.) This packing-case O is placed in the opening in the top of the receiver directly over the mouth of the magazine, as shown in Figs. 15 and 16, when by inserting the thumb in the slot or opening O' (shown in Fig. 16) the mass of cartridges in the case O can be forced directly down through the receiver into the magazine below, as illustrated in said figures. By these means the magazine can be filled at one operation very quickly and without detaching it from the gun, it being the intention to provide a number of these packing-cases, ready filled for use, and which the soldier will carry with him to be used when needed. It is not necessary that there shall be two of these spring-lips, as I find that one can be made to answer the purpose nearly, if not quite, as well. So, too, it is not necessary that the lip or lips should be set inclined, as shown, as it is obvious that they may be arranged to move in a horizontal plane laterally and operate the same, in which case their inner edges would preferably, though not necessarily, be rounded or beveled.

It will readily be seen that a gun thus constructed may be used either as a magazine-gun or as a single-loader, and that, too, without

any change whatever; and, also, that the magazine may be charged by hand, each cartridge being inserted separately, or that by using the packing-case it can be filled by a single operation.

It is obvious that the spring-lips, instead of being connected to the gun, may be secured to the mouth of the magazine and operate the same.

Having thus fully described my invention, what I claim is—

1. The combination, in a gun, of the breech-bolt C and the detachable non-rotating nose-piece G, provided with a tubular stem arranged to fit within the front end of the bolt, the two being connected by a bayonet-joint, whereby the nose-piece is moved to and fro with the bolt C, remains stationary when the bolt is turned to lock or unlock it, and can be disconnected from the bolt without removing the latter from the gun, as herein set forth.

2. The detachable nose-piece G, provided with the lateral projection G', arranged to fill the space between the edge of the extractor H' and the top of the side wall of the receiver, whereby it serves as a gas check or deflector, and also prevents the nose-piece from rotating with the breech-bolt, as shown and described.

3. The rigid extractor H H', in combination with the bolt C and nose-piece G, said parts being constructed and arranged for joint operation, as set forth.

4. The rigid extractor H H', provided with the internal transverse groove, a', in combination with the bolt C, provided with the lug b, for locking said parts together when the bolt is ready to be retracted.

5. The rigid extractor H H', having the projection l' at its rear end, arranged to engage in the recess t' of the rib on the bolt C when the bolt is locked ready for firing, as set forth.

6. The rigid extractor H H', provided with the gas-deflector e', in combination with the nose-piece G, provided with the recess e'', substantially as shown and described.

7. In combination with the bolt C, provided with the rib C', having a recess in its upper side, with the transverse pin f fitted therein, the spring d, provided on its under side with the lug or hook e, and the rigid extractor H H', said parts being arranged to operate substantially as set forth.

8. The firing-pin a, provided with a screw-thread at its rear end, in combination with nut b, and the cocking-piece D, provided with the pin c, for locking said nut in position, substantially as shown and described.

9. The firing-pin a, provided with the collar v, having a slot, v, therein, in combination with the bolt C, provided with the inwardly-projecting lug or pin i', and the cocking-piece D, provided with the guide-pin p, said parts being arranged to operate substantially as and for the purpose set forth.

10. The receiver A, having an opening through its bottom corresponding in size with

the cartridge to be used, in combination with one or more spring-lips arranged to project partially over the mouth of the magazine below, for the purpose of holding the cartridges in proper position to be fed forward by the bolt, enable the magazine to be filled by shoveling the cartridges in from above, and enable the gun to be used as a single-loader when the magazine is empty, as set forth.

5 11. The combination, in a gun, of the slotted receiver A, the spring-lips P at the sides of the receiver and above the mouth of the magazine, the magazine M, and the packing-case O, said parts being constructed and arranged to operate substantially as and for the purpose herein set forth.

15 LOUIS P. DISS.
